PLATE CLAMP

Anthony S. Busk, Paterson, N. J., assignor to
 New Era Manufacturing Company, Paterson,
 N. J., a corporation of New Jersey

Application December 18, 1935, Serial No. 54,997

20 Claims. (Cl. 101—415.1)

My invention relates generally to plate-clamps for printing-press cylinders where it is desired to have substantially the entire circumference of the cylinder utilized for impression or plate-supporting purposes as is common in web printing-presses, and my invention particularly relates to improved clamping mechanisms for fastening flexible sheets or plates in even and firm contact with the printing-press cylinder and is especially 5 adapted for securing the zinc plates wrapped about the cylinders in offset printing-presses, though it may be used to advantage in other types of presses.

The objects of my invention are, among other 15 things, to provide a simple, novel and efficient clamp mechanism for such printing plates which plate-clamps will be convenient to operate and which will strain and hold the plate wrapped about the cylinder surface with a uniform and 20 equalized tension so as to prevent any wrinkles or unevenness on the surface of the plate, thereby ensuring accurate printing; furthermore to provide a plate-clamp mechanism of such a character that permits substantially all the continuous 25 printing surface of the cylinder to be used, which object I accomplish by utilizing the cylinder plate clamping mechanism as part of the cylinder printing surface when the plate has been positioned and secured for printing.

30 A further feature of my invention is the provision of an improved plate-clamp embodied within the cylindrical contour of the cylinder and having the desired attributes of simplicity, efficiency and durability, by which the flexible plate 35 may not only be clamped to the cylinder but also loosened therefrom, both easily and quickly, with the likelihood of mutilation of the plates reduced to a minimum in that the operations of the clamping devices are conveniently located outside the 40 zone of the printing plate wrapped about the cylinder.

With these and other objects in view, my invention comprises the construction, combination and arrangement of the various parts hereinafter 45 described, and then particularly pointed out in the appended claims.

In the accompanying drawings, Fig. 1 is a plan view of the press cylinder, partly broken away to show the structure of the plate-clamp, the 50 right portion of this figure showing a portion of the flexible plate wrapped about the cylinder in clamped position;

Fig. 2 is a sectional view on the line 2—2 of Fig. 1;

Fig. 3 is a sectional view similar to Fig. 2, but

showing the cylindrical segment withdrawn below the peripheral surface of the cylinder when the plate is to be loosened and removed;

Fig. 4 is a detailed end view looking from the right of Fig. 1;

Fig. 5 is an enlarged detailed section showing the plate ends held by the clamp with a practically continuous printing surface for the cylinder; and

Fig. 6 is a perspective view of the flexible plate. 10

Similar numerals refer to similar parts throughout the several figures.

Referring to the drawings and particularly to Fig. 1, the press cylinder 7 is of the usual hollow construction having the peripheral cylindrical side walls 8 with the bearers 9 and 10 at either end, the cylinder 7 being mounted on the axially-disposed supporting shaft 11 to which is fastened the driving gear 12. Integral with the cylinder 7 and bearers 9 and 10 is the irregular shaped counter-sunk web 13 (Figs. 2 and 3), which terminates with the cylinder side walls 8 to form the transverse edges 14 and 15 coincident with the peripheral surface of the cylinder 7 with the transverse gap or wide slot 16 within which is fitted the transverse cylindrical segment 17 of the same degree of curvature as the side walls 8 of the cylinder 7, as shown in Figs. 1 and 2.

The cylindrical segment 17 carries lugs 18 at either end journalled in the stud-bolts 19 that are secured in holes 20 drilled in either end of the cross-shaft 21, the stud-bolts 19 being journalled in the bearers 9 and 10 as shown in Fig. 1. To the outer ends of the stud-bolts 19 are keyed the brackets 22 to which are pivoted the short rods 23 that are adapted to slide in the apertured lugs 24 fastened to the bearers 9 and 10 as shown in Fig. 1. Coiled about the rods 23 between the lugs 24 and the inner base of the rods 23 (Figs. 1 and 4) are the two compression springs 25 that normally hold the depending brackets 22 in their radial position as shown in Fig. 4. The outer surfaces of the brackets 22 and adjacent ends of the stud-bolts 19 have holes 26 formed therein for the insertion of any suitable pin-bar or bolt 27 (shown in dot and dash lines in Fig. 4) to rock the brackets 22 in an anti-clockwise direction as shown by the arrow in Fig. 4 against the tension of the springs 25.

The cylindrical segment 17 is so shaped that its outer surface 28 when the segment is raised to its normal operative position (Fig. 2) snugly fits within the transverse opening 16 and is a part of the printing surface of the cylinder 7 extending from the transverse edge 15. When the segment 50

17 is lowered by pivoting on the cross-shaft 21 to its Fig. 3 position, it no longer forms a part of the printing surface between the transverse edges 14 and 15 of the cylinder 7 and no longer is in 5 contact with, nor does it serve as a support for, the flexible plate P shown as wrapped about the cylinder 7 (Figs. 2 and 3).

Means for raising and lowering this segment 17 on its pivoted support on the cross-shaft 21 10 may be widely varied: In the embodiment illustrated in Figs. 1-4, I have shown a preferred mechanism which effectively accomplishes this purpose. Extending inwardly from the lugs 18 of the segment 17 are spaced apart webs in the 15 form of integral short arms 29 (four being shown in dotted lines in Fig. 1). Fastened to the outer (and lower) ends of the arms 29 are four rounded flat plates 30, preferably of hardened steel. Opposite and in spaced parallelism with the plates 20 30 are rounded flat buttons 31, also preferably made of hardened steel, that are welded or rigidly secured to the body of the web 13. Extending transversely through the cylinder 7 and journalled in the bearers 9 and 10 is the cylindrical cross 25 shaft 32 arranged between the plates 30 and buttons 31 with flat cut-out portions 33 formed in the cylindrical surface of the shaft 32 between the oppositely disposed plates 30 and buttons 31, all as shown in Figs. 1-3. Pinned to the end of 30 the shaft 32 adjacent the bearer 10 is the circular boss 34 having the hole 35 cut in its outer surface for the insertion of a pin-bar 36 (shown in dot and dash lines in Fig. 4) in order to shift the boss 34 and so rock the shaft 32 in either direction. 35

The boss 34 has formed therein the elongated concentric slot 37 through which projects the threaded bolt 38 having the squared head 39 by which the position of the cross-shaft 33 and boss 34 may be rigidly secured in any predetermined position within the slot 37. Fig. 2 shows the plates 30 and buttons 31 braced apart to hold the segment 17 in its raised position coincident with the sidewalls 8 of the cylinder 7, while Fig. 3 shows the cut-out portions 33 of the shaft 32 in surface-to-surface contact with the flat plates 30 to permit the segment 17 to swing inwardly on the shaft 21 below the cylinder surface, and so out of contact with the plate P.

The plate-clamping mechanism proper comprises the cross-shaft 21 that rocks in either direction (Fig. 1), the under part 40 of the cross-shaft bearing on a flat elongated plate 41, preferably of hardened steel, which is secured transversely across the cylinder below the transverse edge 14. As shown in Figs. 2 and 3 the shaft 21 has a limited rocking movement with its under part 40 bearing on the plate 41. Projecting upwardly from, and integral with, the shaft 21 is 50 the clamping plate 42 with its upper end having a recessed portion 43 (Fig. 5) and its top or exposed surface lying in parallelism with the transverse edge 14 in the small opening between the edge 14 and the adjacent edge 44 of the segment 17 and coincident with the cylindrical surfaces 55 of the cylinder 7 and segment 17.

When the stud-bolts 19 are rocked by the brackets 22 against the tension of the springs 25, the clamping plate 42 on the shaft 21 has a limited rocking movement between the transverse edge 14 and the segment 17 with the under part 40 bearing on the plate 41 (Fig. 1).

The plate P is shown in Fig. 6 and is the customary flexible plate of zinc for use in offset 75 printing. Each end of the plate P has right-

angled bent-over ends 45 and 46 to a depth of about $\frac{1}{4}$ inch. The distance between the bent edges 45 and 46 of the plate P is equal to the circumference of the cylinder 7 less twice the thickness of the plate P as shown in Figs. 2, 3, 5 and 5.

In operation in fastening the plate P to the cylinder 7, the pressman inserts the pin-bar 36 in the hole 35 and moves the bar 36 in the direction of the arrow in Fig. 4, which movement 10 rocks the shaft 32 so that the cut-out portions 33 come into surface contact with flat plates 30 so as to permit the segment 17 to drop or swing inwardly on the stud-bolts 19 as shown in Fig. 3 with outer surface of the segment 17 below or 15 inside the periphery of the cylinder 7 itself. The stud-bolts 19 journalled in the cross-shaft 21 are then moved by the pin-bar 27 to the left in Fig. 4 which swings the clamping plate 42 to the right in Fig. 3 against the tension of the springs 20 25. Then the front bent-over end 45 of the plate P is placed transversely between the cylinder edge 14 and the clamping plate 42 which is then allowed to pinch the plate end 45 against the transverse edge 14 by the force of the released 25 springs 25. The cylinder 7 is then rotated one revolution so as to wrap the plate P about the cylinder. Thereafter the clamping plate 42 is 30 opened again by moving same in a clockwise direction in Fig. 3, and the rear end 46 of the 35 plate P is fitted over the top of the clamping plate 42 (Figs. 3 and 5) and adjacent the front end 45 so that the clamping plate 42 holds both plate ends 45 and 46 in surface-to-surface contact with the transverse edge 14. Then by means 40 of the pin bar 36, the pressman turns the shaft 32 until the full diameter of the shaft is wedged between the plates 30 and buttons 31 thereby raising the segment 17 to its Fig. 2 position with the periphery of this segment forming a part of 45 the true periphery of the cylinder 7 (Fig. 2).

This raising of the segment 17 to the position shown in Figs. 2 and 5 strains and holds tight the plate P wrapped about the cylinder 7 to bring the plate in accurate position for printing. 45 The pressman then locks the segment 17 in its normal position to hold the plate by screwing home the threaded bolt 38 by means of a wrench acting on the squared head 39 to prevent any rotary movement of the shaft 32. 50

To loosen and remove the plate P from the cylinder 7, the operations are substantially the same but in a reverse order, and need not be described in detail except that should the segment 17 fail to drop from its Fig. 2 position 55 when the shaft 32 is rotated to its Fig. 3 position, a slight movement of the clamping plate 42 in a clockwise position in Fig. 3 will lower the segment 17 and so release the tension on the plate P so that its bent-over ends 45 and 46 may be 60 sequentially detached from their mutual surface contact in the narrow opening between the transverse edge 14 and adjacent recessed portion 43 of the clamping plate 42. (Figs. 2, 3, and 5.)

According to my invention I have employed 65 the segment 17 together with the top surface of the clamping plate 42 as part of the cylinder printing surface as well as an element in the clamping mechanism so as to permit the use for printing of practically the entire circumferential 70 printing surface of the cylinder 7 as clearly shown in Fig. 5.

My invention is not to be restricted to the precise details of construction shown, since various changes and modifications may be made 75

therein without departing from the scope of the invention or sacrificing the advantages derived from its use.

I claim as my invention:

5 1. In a printing cylinder having a gap and having a flexible plate wrapped about the cylinder with both bent-over ends of the plate arranged in mutual parallelism within the gap adjacent one of the edges of the gap, a clamping member, and means for yieldingly moving said member angularly with respect to the cylinder to grip both bent-over ends of the plate against said edge.

10 2. A printing cylinder having a gap, a clamping member within the gap to grip both ends of a flexible plate wrapped about the cylinder, and spring-pressed means for holding said member against the plate ends to press the latter against one of the edges of the gap.

15 3. A printing cylinder having a gap, a clamping member within the gap to grip both ends of a flexible plate wrapped about the cylinder, spring-pressed means for holding said member against the plate ends to press the latter against one of the edges of the gap, and a plate-supporting segment movable outwardly within the gap for tensioning the plate on the cylinder.

20 4. A printing cylinder having a gap, a clamping member within the gap to grip both ends of a flexible plate wrapped about the cylinder, spring-pressed means for holding said member against the plate ends to press the latter against one of the edges of the gap, and a plate-supporting segment movable outwardly within the gap to bring 30 the segment surface coincident with the cylinder surface for tensioning the plate on the cylinder.

25 5. A printing cylinder having a gap, a clamping member within the gap to grip both ends of a flexible plate wrapped about the cylinder, spring-pressed means for holding said member against the plate ends to press the latter against one of the edges of the gap, and a plate-supporting segment adjacent said clamping member and movable outwardly within the gap for tensioning the 35 plate on the cylinder, while forcing the clamping member against the plate ends to lock the plate on the cylinder in printing position.

30 6. A printing cylinder having a gap, a longitudinally-disposed clamping plate within the gap in parallelism with one of the edges of the gap, spring-pressed means normally forcing said clamping plate against the bent-over ends of a flexible plate wrapped about the cylinder to grip and hold the ends against said edge, a plate-supporting segment pivoted within the gap to form a part of the cylinder surface, and means for raising and lowering said segment without moving the clamping plate to tension and loosen the plate on said cylinder.

35 7. A printing cylinder having a gap, a longitudinally-disposed clamping plate within the gap in parallelism with one of the edges of the gap, spring-pressed means normally forcing said clamping plate against the bent-over ends of a flexible plate wrapped about the cylinder to grip and hold the ends against said edge, a plate-supporting segment pivoted within the gap to form a part of the cylinder surface, and means for raising said segment coincident with the periphery of the cylinder to tension and for lowering said segment out of contact with the plate to loosen the latter without moving the clamping plate.

40 8. A printing cylinder having a gap, a longitudinally-disposed clamping plate within the gap

in parallelism with one of the edges of the gap, spring-pressed means normally forcing said clamping plate against the bent-over ends of a flexible plate wrapped about the cylinder to grip and hold the ends against said edge, a plate-supporting segment pivoted within the gap to form a part of the cylinder surface, means for raising and lowering said segment without moving the clamping plate to tension and loosen the plate on said cylinder, and means for locking said last means in either position.

45 9. A plate-clamp for holding a flexible plate having right-angled bent-over ends and wrapped about a printing cylinder having a gap comprising a spring-pressed clamping member to grip and hold the plate ends interposed between the member and one of the edges of the gap, and a plate-supporting segment movable within the gap to tension the plate on the cylinder and form a part of the cylinder surface, one edge of the segment bearing 50 on the clamping member opposite to the plate ends to lock the plate under tension on the cylinder.

55 10. A plate-clamp for holding a flexible plate having right-angled bent-over ends and wrapped about a printing cylinder having a gap comprising a spring-pressed clamping member to grip and hold the plate ends interposed between the member and one of the edges of the gap, and a plate-supporting segment adjacent said clamping member and movable within the gap to tension the plate on the cylinder and form a part of the cylinder surface, one edge of the segment bearing 60 on the clamping member opposite to the plate ends to lock the plate under tension on the cylinder.

65 11. A plate-clamp for holding a flexible plate having right-angled bent-over ends and wrapped about a printing cylinder having a gap comprising a spring-pressed clamping member to grip and hold the plate ends interposed between the member and one of the edges of the gap, a plate-supporting segment pivoted within the gap adjacent said clamping member to form a part of the cylinder surface when forced into contact with the plate adjacent one of the plate ends, and means for raising said segment with one edge thereof bearing on the clamping member to lock the plate under tension on the cylinder, the surface of the segment in its raised position being 70 coincident with the periphery of the cylinder.

75 12. In a printing cylinder having a gap and having a flexible plate wrapped about the cylinder with both bent-over ends arranged in mutual parallelism within the gap adjacent one of its edges, a single clamping member pivotally mounted within the gap, and means for yieldingly forcing said member to rock angularly with respect to the cylinder to grip both bent-over ends of the plate against said edge, the top surface of said clamping member forming a part of the supporting surface for the plate on the cylinder.

80 13. A plate-clamp for positioning a flexible plate wrapped about a printing cylinder having a gap comprising a single pivotally mounted clamping member, means for moving said member angularly within the gap to first lock both bent-over ends of the plate in surface-to-surface contact against one edge of the gap, a plate supporting segment adjacent the clamping member, and means for thereafter moving said segment outwardly within the gap substantially to the periphery of the cylinder to tension the plate on the cylinder, the top surfaces of the clamping member, said segment and the cylinder support- 75

ing substantially the entire under surface of the plate.

14. A plate-clamp for positioning a flexible plate wrapped about a printing cylinder having a gap comprising a single longitudinally disposed pivotally mounted clamping member, means for moving said member transversely within the gap to first lock both bent-over ends of the plate in surface-to-surface contact against one edge of the gap, a plate supporting segment adjacent the clamping member, and means for thereafter moving said segment outwardly within the gap substantially to the periphery of the cylinder to tension the plate on the cylinder, the top surfaces of the clamping member, said segment and the cylinder supporting substantially the entire under surface of the plate.

15. A plate-clamp for positioning a flexible plate wrapped about a printing cylinder having a gap comprising a single pivotally mounted clamping member, means for moving said member angularly within the gap to first lock both bent-over ends of the plate in surface-to-surface contact in mutual parallelism against one edge of the gap, a movable plate-supporting segment within the gap to tension the plate on the cylinder, and means for thereafter moving said segment outwardly and substantially to the periphery of the cylinder, the top surfaces of the clamping member and the segment forming a substantially continuous part of the cylinder surface.

16. A plate-clamp for positioning a flexible plate wrapped about a printing cylinder having a gap comprising a single pivotally mounted clamping member, means for moving said member angularly within the gap to first lock both bent-over ends of the plate in surface-to-surface contact in mutual parallelism against one edge of the gap, a movable plate-supporting segment within the gap to tension the plate on the cylinder, and means for thereafter moving said segment outwardly and substantially to the periphery of the cylinder, the top surfaces of the clamping member and the segment forming a substantially continuous part of the cylinder surface, and means for withdrawing the segment within the cylinder gap to loosen the plate on the cylinder without moving the clamping member from its locked position.

17. A printing cylinder having a gap, a single pivotally mounted clamping member, means for

moving said member transversely within the gap to first lock both bent-over ends of a flexible plate in surface-to-surface contact against one edge of said gap, a plate supporting segment, means for thereafter moving said segment outwardly within the gap substantially to the periphery of the cylinder for tensioning the plate, the top surfaces of the clamping member, said segment and the cylinder supporting substantially the entire under surface of the plate.

18. A printing cylinder having a gap, a single pivotally mounted clamping member, means for moving said member angularly within the gap to first lock both bent-over ends of a flexible plate in surface-to-surface contact against one edge of said gap, a plate supporting segment, and means for thereafter moving said segment outwardly within the gap substantially to the periphery of the cylinder for tensioning the plate, the top surfaces of said clamping member and of said segment being adjacently coincident with the periphery of the cylinder.

19. A printing cylinder having a gap, a single pivotally mounted clamping member, means for moving said member transversely within the gap to first lock both bent-over ends of a flexible plate in surface-to-surface contact against one edge of said gap, a plate supporting segment, and means for thereafter moving said segment outwardly within the gap substantially to the periphery of the cylinder for tensioning the plate independently of the clamping member and without moving the latter, the top surfaces of the clamping member, said segment and the cylinder supporting substantially the entire under surface of the plate.

20. A printing cylinder having a gap, a single pivotally mounted clamping member angularly within the gap to first lock both bent-over ends of a flexible plate in surface-to-surface contact against one edge of said gap, a plate supporting segment, and means for thereafter moving said segment outwardly within the gap substantially to the periphery of the cylinder for tensioning the plate independently of the clamping member and without moving the latter, the top surfaces of said clamping member and of said segment being adjacently coincident with the periphery of the cylinder.

ANTHONY S. BUSK.
